STREET SWEEPING MACHINE

Carl W. Mott, La Grange Park, Ill., assignor to
Elgin Sweeper Company, Elgin, Ill., a corpora-
tion of Illinois

Application January 2, 1948, Serial No. 175

7 Claims. (Cl. 15—83)

1

This invention relates to improvements in street sweeping machines, and more particularly to machines of the type which sweep up and collect dirt and debris from the surface of a street as the machine is propelled therealong, the sweepings being collected in a dirt box or hopper carried by the machine.

As commonly constructed, street sweeping machines include a dirt box into which sweepings are directed from the sweeping brush, and means are provided at the bottom of the dirt box for dumping the collected contents when the dirt box is to be evacuated. However, the evacuated contents can assume only a shallow pile where the receiving surface is at the traction level of the wheels of the sweeper, or the sweeper must be run to the edge of a depression which is to receive the evacuated contents. Where no permanent dump is handy to the sweeper in the particular area or zone in which it is operating, it generally is necessary for the sweeper periodically to dump its contents of accumulated sweepings in the street or other prescribed place for pick-up by a truck which will haul the same to a disposal point. This requires re-handling of the sweepings and adds a substantial labor and handling cost to the street sweeping operations.

An important object of the present invention is to provide a street sweeping machine which is so constructed and arranged that sweepings collected thereby can be dumped directly into the hopper or body of a truck or onto a relatively high pile of sweepings directly at a disposal point where that is convenient.

Another object of the invention is to provide a street sweeping machine having an elevating type of dirt box which can be raised to a substantial height for disposition in overlying relation to a truck body or the like which is to receive the accumulated sweepings from the dirt box.

Another object of the invention is to provide in a street sweeping machine means for receiving and accumulating a substantial volume of sweepings at a point relatively close to the sweeping brush assembly of the machine and which is adapted to be moved to an elevated position to permit dumping of the accumulated contents of the sweepings therefrom to an elevation substantially above the normal operating elevation of the machine.

According to the general features of the present invention there is provided in a street sweeping machine having sweeper brush means and a dirt box for receiving and accumulating mate-

2

rials swept up by the brush assembly, means for selectively elevating said dirt box to a height substantially above its dirt-receiving height for dumping the contents thereof at a substantially greater elevation than the normal dirt collecting elevation of the dirt box.

According to other general features of the invention, the means for elevating the dirt box comprises a parallel linkage system.

10 According to additional general features of the invention, the means for elevating the dirt box includes hydraulic actuation mechanism.

15 According to still other general features of the invention, there is provided in a street sweeping machine of the type which is propelled along a street to be swept and has a sweeping brush structure, a dirt box, means for directing sweepings from the brush structure into the dirt box, the dirt box being detachably associated with the machine, and means connecting the dirt box to the machine and constructed and arranged to respond to the will of the operator of the sweeping machine to lift the dirt box to an elevated position from which the contents 20 of the dirt box can be dumped into the body of a truck in which the dumped sweepings can be hauled away from the sweeping site.

25 Other objects, features and advantages of the present invention will be readily apparent from the following detailed description of a preferred embodiment thereof taken in conjunction with the accompanying drawings, in which:

30 Figure 1 is a side elevational view, more or less schematic, showing a street sweeping machine embodying the features of the present invention;

35 Figure 2 is a top plan view of the street sweeping machine; and

40 Figure 3 is a fragmentary side elevational view of the machine of Figure 1 and a portion of a truck and showing how sweepings accumulated by the sweeping machine can be dumped into the truck to be hauled away.

45 The present invention is especially applicable to self-propelled street sweeping machines, such as that illustrated, and including a body 10 supported on a chassis 11 resting upon a three wheel arrangement including a single rear wheel 12 and a pair of spaced coaxial front wheels 13.

50 The machine is propelled by suitable driving connection between the wheel assembly and a motor, such as a gasoline engine within a rear housing 14. In Figures 1 and 3, the particular manner in which the front wheels 13 are connected to 55 the chassis 11 has been omitted to avoid obscuring

ing what, for the purpose of the present disclosure, are more important features and since the details of the undercarriage and wheel drive are well known structures. The machine is operated by a person adapted to be seated within an operator's compartment 15 located at an intermediate point in the body 10 forwardly of the engine compartment 14. A steering wheel 17 may be provided by which the rear wheel 12 is controlled to steer the direction of travel of the machine.

Underneath the chassis 11 and between the wheels 12 and 13, is located a cylindrical main sweeping broom 18 which is supported by arms 19 and is operable to rotate sweepingly forwardly, as indicated by directional arrow to sweep up dirt and litter from the street along which the machine is propelled into a downward extension 20 of the body 10 providing a forward sweepings accumulator. The machine is also equipped with the customary rotary side brooms or brushes 21 by which accumulations of litter in the gutters of the street being cleaned are swept into the path of the main cylindrical sweeping broom 18.

According to the present invention the sweepings accumulated by the machine are deposited in a receptacle or dirt bucket 22 which is separably connected to the forward end of the body 10, and is arranged to be elevated to a substantial height above its dirt receiving position with respect to the body 10 of the sweeping machine. To this end, the dirt bucket 22 is, in the present instance, in the form of a hopper or bucket having an open upper end and a capacious sweepings receiver interior 23. The open top of the dirt box 22 is preferably disposed in an operative oblique upward and forwardly inclined plane and is arranged to make substantially dirt-tight engagement with an upper, overhanging forwardly extending dirt delivery portion 24 of the body 10 having the forward part thereof which is engaged by the top of the dirt bucket arranged in complementary oblique plane and opening forwardly to provide communication from the interior thereof into the dirt bucket. Thereby sweepings directed into the lower body portion 20 by the broom 18 are adapted to travel in the general direction indicated by the dash directional arrow lines D up through the lower body portion 20 which has a slanting forward wall 25 coplanar with the front of the portion 24, and then through the upper forward portion 24 of the body into the dirt bucket 22. The lower end of the dirt bucket 22 is, of course, disposed at a sufficient normal elevation to clear objects and structures that may appear in the path of the machine and protrude above the traction level of the front wheels 13 in the course of the street sweeping activity of the machine.

Sweepings which accumulate in the dirt bucket 22 are adapted to be dumped through the forward end of the dirt bucket which is normally closed by a dump door 27 which is preferably hingedly mounted at its upper edge as at 28 to swing downwardly and forwardly to open position substantially as indicated in Fig. 3. Means for controlling the dump door 27 preferably comprises a pair of hydraulic operators 29 having respective connections through crank arms 29a with the pivot 28 of the dump door and which may be in the form of a rotatably mounted shaft rigidly attached to the dump door.

By mounting the dirt bucket 22 in such a manner that it can be swung forwardly and upwardly from the body portion 24, it can be elevated to a

point where its contents may be dumped by opening of the dump door 27 into a truck T (Fig. 3) or onto a substantially elevated pile of debris and sweepings accumulated from a number of 5 dumpings of sweepings. This is accomplished by means such as a parallel linkage system by which the dump bucket 22 is connected to the body 10. Herein the parallel linkage system includes respective pairs of identical links at the 10 opposite sides of the dump bucket and including in each instance a lower link 30 and an upper link 31. The lower link 30 is connected on a forward pivot 32 adjacent the lower corner of the dirt bucket 22 and at its rear end on a pivot 33 15 adjacent the uppermost corner at the side of the forward body portion 24. The upper link 31 is connected at its forward end in vertically spaced relation on a pivot 34 to the side of the dirt bucket 22 and at its rear end on a pivot 35 in vertically 20 spaced relation above the pivot 33 of the lower link, a vertically upwardly extending bracket 31 being carried by the body 10 to accommodate the link pivot 35.

To actuate the parallel linkage to move the 25 dirt bucket 22 between dirt receiving association with the body portion 24 and a highly elevated position as shown in Figure 3, appropriate hydraulic operators 38 are connected to the upper links 31 adjacent their rear ends and preferably 30 to rearwardly and downwardly extending ears or arms 39 on such links. The respective hydraulic operators are connected at their rear ends on respective pivots 40 on the respective sides of the body 10 and at their forward ends through the 35 medium of respective piston rods 41 on pivots 42 with the link arms 39. Any preferred hydraulic operating circuit may be utilized for actuating the hydraulic operators 38 and the hydraulic operators 29, there preferably being provided conveniently accessible control means for the operator of the machine, such as a manually engageable lever, knob or other manipulator 43 in the operator's compartment 15 for this purpose.

While the sweeping machine is in a sweeping 45 run, the dirt bucket 22 is held in tight dirt receiving association at its open upper end with the open forward end of the body portion 24. In this the weight of the dirt bucket is an important factor in view of the disposition of the 50 supporting and connecting parallel linkage 30-31, and this may be supplemented by a hydraulic latch afforded by the hydraulic operators 38, or any other suitable latching means may be utilized.

When it is desired to dump accumulated sweepings from the dirt box or bucket 22, the machine 55 may be run directly to a dumping site and, if desired, the contents of the dirt bucket may be dumped to the traction plane of the wheels 13 merely by opening the dump door 27. Should it be necessary to deposit the sweepings on a pile at a higher elevation than the lower end of the dirt bucket 22 in its sweepings receiving position, then the dirt bucket can be elevated to the necessary extent up to its uppermost elevated limit by operation of the hydraulic operators 38, whereafter the dump door 27 is adapted to be opened for discharging the contents of the bucket. Such elevation of the dirt bucket 22 is, of course, effected before the machine is driven to the point where the bucket overhangs the spot to which its contents are to be dumped, the machine then being propelled to carry the bucket over said spot.

A great convenience is afforded by the present elevating type of dirt bucket and substan-

tial street sweeping economies are effected under circumstances where the area in which the streets are being swept is remote from a dumping site and the sweepings must be hauled some distance to such a site. Under these circumstances, when it is desired to evacuate the dirt bucket 22, it is elevated to a sufficient height, and either the sweeping machine is driven to carry the dirt bucket over the body of the truck T or the truck T is backed under the elevated dirt bucket and the sweepings contents of the dirt bucket discharged as indicated by the directional arrows in Figure 3 upon opening of the dump door 27.

Inasmuch as the dirt box or bucket 22 is supported by the parallel linkage 30-31, its axis does not shift in any position thereof as it is swung between loading and dumping positions as indicated by the dash line S in Figure 3. Thus, there is no danger of spilling of the contents as the dirt bucket is elevated.

From Figures 1 and 2, it may be observed that the dirt box or bucket 22 is preferably dimensioned so as to blend harmoniously with the forward portion of the sweeper machine body 10. That is, the upper surface of the dirt bucket is preferably formed to blend coplanar with the front to rear curvature of the top of the body 10. The sides of the dirt bucket are preferably formed to extend in the same planes as the respective sides of the body 10. This not only affords an attractive appearance for the machine as a unit, but also facilitates and simplifies the construction of the machine.

Where preferred, of course, the relationship of the mouth of the dirt bucket 22 to the sweeping broom 18 may be such that the sweepings will be impelled directly into the dirt bucket.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. In combination in a street sweeping machine including a body having an obliquely upwardly and forwardly arranged open front face portion, means for sweeping a surface over which the machine is directed and delivering the sweepings to said open front face portion, a dirt bucket having its major axis normal to said oblique front face portion and having its upper end cooperatively related to said oblique front face portion to receive the sweepings, and means connecting the dirt bucket to the sweeper body for movement bodily of the bucket into an elevated position separated from said front face portion, said bucket having a removable portion at an end remote from said open face portion displaceable, when the bucket is elevated, for the discharge of the bucket contents.

2. In combination in a street sweeping machine including a body having an obliquely upwardly and forwardly arranged open front face portion, means for sweeping a surface over which the machine is directed and delivering the sweepings to said open front face portion, a dirt bucket having its major axis normal to said oblique front face portion and having its upper end cooperatively related to said oblique front face portion to receive the sweepings, and means connecting the dirt bucket to the sweeper body for movement bodily of the bucket into an ele-

vated position separated from said front face portion, said bucket having a removable portion at an end remote from said open face portion displaceable, when the bucket is elevated, for the discharge of the bucket contents, said connecting means comprising a parallel linkage including a lower link pivotally connected at one end to the side of the dirt bucket adjacent its lowermost corner and at its other end connected pivotally to the uppermost forward side portion of the sweeper body and a second link connected pivotally to the side of the dirt bucket in spaced vertical direction above the lower link and to a fixed pivot in spaced relation above the lower link and in fixed relation to the body, whereby in the separation of the dirt bucket from said forward face of the body the dirt bucket swings on an arc forwardly and upwardly when said removable portion is adapted to be displaced.

3. In a power-propelled sweeping machine having a body carried upon power-driven aligned traction wheels and a broom for sweeping dirt into said body, a dirt receptacle having an opening at one side in communication with said body for receiving sweepings as the same are swept up by the broom, means for holding said receptacle in fixed position on said body to receive the sweepings and for bodily moving said receptacle away from said body to disconnect same therefrom so that the receptacle may thereafter be emptied, said receptacle having a portion thereof provided with a discharge door normally held closed during loading of the receptacle with sweepings and adapted to be opened after removal of the receptacle from cooperation with the body to enable discharging of the load from the receptacle.

4. In a sweeping machine, including a hollow body for receiving the sweepings and formed open at one end and for the discharge of sweepings therethrough, a closure member for covering said open end and comprising a bucket having an open side in communication with the interior of said body for receiving and storing said sweepings discharged through said open end and means for holding said bucket in closure position against said open end of the body during said sweeping operation and for bodily swinging said bucket away from said open end and to an elevated discharge position substantially above and remote from said open end, said bucket also having a closure removable from over a discharge opening in the bucket when the bucket is elevated and so that the bucket contents can be discharged through said discharge opening.

5. In a sweeping machine, including a hollow body for receiving the sweepings and formed open at one end and for the discharge of sweepings therethrough, a closure member for covering said open end and comprising a bucket having an open side in communication with the interior of said body for receiving and storing said sweepings discharged through said open end and means for holding said bucket in closure position against said open end of the body during said sweeping operation and for bodily swinging said bucket away from said open end and to an elevated discharge position substantially above and remote from said open end, said bucket having a closure removable from over a discharge opening in the bucket when the bucket is elevated and so that the bucket contents can be discharged through said discharge opening, said bucket 75 when in closure position on the body being held

so as to depend downwardly from said open end and as a continuation of the body in an inclined position for the sweepings to gravitate freely therein toward the bucket closure, and when in elevated position being substantially above the plane of the top of the body and being held in an inclined position with said discharge opening lowermost.

6. A machine of claim 3 further characterized by said body having a lower portion provided with a sweeping discharge opening and said receptacle having a top portion provided with an inlet charging opening and held against said body lower portion by said means when the receptacle is being loaded with sweepings, said portions being separable by said means to move said receptacle away from and out of engagement with said body lower portion.

7. The machine of claim 3 further characterized by said means including pivot means on the sides of the receptacle, leverage means connected to said pivot means and power-actuated means connected to said leverage means for moving the receptacle into an outer cooperation with a downwardly discharging portion of the body, said receptacle having an upper portion

provided with a charging opening and adapted to be moved into registering engagement with said discharging portion of the body by said means.
